UNITED STATES PATENT OFFICE.

FRANK H. BILLS, OF SPRINGFIELD, MASSACHUSETTS.

DANDY-ROLL.

SPECIFICATION forming part of Letters Patent No. 694,717, dated March 4, 1902.

Application filed December 23, 1901. Serial No. 86,877. (No model.)

To all whom it may concern:

Be it known that I, FRANK H. BILLS, a citizen of the United States of America, and a resident of Springfield, in the county of 5 Hampden and State of Massachusetts, have invented certain new and useful Improvements in Dandy-Rolls, of which the following is a full, clear, and exact description.

This invention relates to improvements in 10 dandy-rolls employed in paper-machines, and more particularly pertains to the construction of the supporting-shell, having the conformation of a cylinder, for supporting the usual longitudinal wires, winding-wire, and 15 outer gauze or cloth covering.

The objects of the invention are to devise 20 a construction of an open-work cylindrical frame which, first, is simple and practicable of construction—that is, susceptible of being produced comparatively quickly, easily, and 25 cheaply—which is, secondly, lighter and composed of less wire than ordinarily employed in the dandy-roll frame, due account being taken of requisite strength, stiffness, and stability, and which, thirdly, by reason of the 30 fact that the arrangement of the approximately diamond-shaped spaces comprised within the several crossing wires, which brings the apexes of the successive diamonds in the 35 longitudinal aspect of the roll in helical or spiral lines instead of in lines parallel with the axis, the tendency of the roll to throw water radially and materially in the line of travel of the paper is avoided, for as a matter 40 of fact in this roll its tendency is to cause the unavoidable moisture which accumulates within the roll to have a progression substantially in the direction of the length of the roll, and thus the spraying or spattering 45 of the nearly-finished paper which has passed beyond the dandy-roll, and which spattering causes dark or mottled spots in the paper, is avoided. And by being able to make the supporting structure, which while 50 fulfilling all the requisites thereof, much more open and with wider interstices than is ordinarily found in dandy-roll frames, the frothing effect in the use of the roll is measurably lessened, and, moreover, the washing out or cleaning of the roll, generally performed by forcing water thereinto through a hose, is somewhat more easily performed,

especially by reason of the spiral trend, hereinabove alluded to, of the intersections of the wires composing the supporting-frame, 55 whereby the dislodgment of the fibers of the paper-stock under the action of the forced water becomes facilitated.

The invention is characterized by a cylindrical open-work frame comprising a series 60 of suitably heavy wires, which are suitably spaced and run substantially spirally in parallelism with each other from end to end of the roll, said series of wires of uniform spirality of course having no contact or direct 65 connection one with another, and one or more other wires running spirally in the same direction as the aforementioned series of separated and parallel spiral wires, but having a different pitch or degree of spirality, 70 whereby it crosses and has engagement or connection with each and every one of the aforementioned series of spirally-progressing wires, and the connection or engagement of the one wire with the series of wires of different pitch under this invention is by interweaving, the one wire or "truss-wire," as it may be termed, alternately crossing over one and under the next one of the said series, and each wire which, as the case may be, is 75 innermost at the place of intersection has an approximately semicircular bend or crimp therein, all whereby almost entirely all the lengths of all of the spiral wires have their outer surfaces brought out to and conformable to the surface of a cylinder. 85

The improved roll is shown in the accompanying drawing, which is a plan view of a sufficient portion of the length of a dandy-roll, and which shows especially the novel combination and arrangement of a series of parallel spirally-coursed wires and the truss-wire running spirally in the same direction, but with a different pitch, and showing the one end head for the roll, portions of the longitudinal wires, the winding-wire, and the outer wire cloth or gauze covering. 90

In the drawing the supporting cylindrical structure or frame of the dandy-roll is shown as composed of four wires 1, 2, 3, and 4, having long running coils or spiral courses and running in parallelism with suitable separation, and 5 represents the intersecting and interwoven truss-wire, also comprising a suc- 100

cession of spiral coils, the pitch or trend of the spiral being in the same direction as that of the four parallel running coiled wires aforesaid; but the pitch or trend of this wire 5 is 5 not nearly as sharp or rapid as that of the other wires, so that the truss-wire 5 in its longitudinal course will cross each and every one of the wires 1, 2, 3, 4, and 5. It is practicable to have the wire 5 coiled, for instance, 10 six times as frequently in the length of the roll as are the other and more elongated coils of the other wires. This may be perceived in the drawing by following the course of the wire 1 from its end at the left to the point 1^a, 15 endwise therebeyond, whereat this wire completes one convolution, and noticing that the wire 5 in the distance at the left from 1 to 1^a makes about six convolutions. The wire 5 being in contact with and being secured to 20 each and every one of the other wires of longer spirality at the points of intersections amply braces and stiffens the structure. The truss-wire 5 crosses over one, then under, and next over the wires of longer spirality in its inter- 25 section, respectively, therewith, attaining the advantage of a weaving connection or engagement, and at the intersections whichever of the wires is relatively innermost, whether it be the more closely coiled wire 5 or the 30 other wires 1 to 4, are formed with crimps or approximately semicircular bends, as indicated at o in the drawing, for the accommodation of the relatively outer wires and to permit all portions of the length of every wire 35 except its crimped portions to uniformly lie at the periphery of a cylinder of the proper size. The wires at their places of intersection and contact are secured by solder, which is regarded as the most practical means for 40 final connection.

On the cylindrical open-work structure constituted as described are supported the longitudinal wires d, the winding-wire f, and the outer gauze covering g, and the roll is 45 equipped with end heads h and gudgeons, all as usual in dandy-rolls.

I may employ more than one of the truss-wires 5, having the spirality different from that of the several wires 1 2 3, &c.; but the 50 employment of one wire, as shown, is sufficient for all practical purposes.

I am aware that dandy-rolls have been made in which wires running spirally in opposite directions are employed and in which 55 the one set of wires while having crimped relations at the intersections with the other set is entirely within the other set, there be-

ing no interweaving, and such already-known roll when properly constructed for adequate strength and stability more wires are employed than I need to employ, resulting in more intersections at the points of the diamond spaces, which points range regularly and longitudinally in comparatively frequent lines on the face of the roll; but I believe it 60 to be new and highly advantageous to construct a roll with a wire thereof running spirally in the same direction as the spirality of a plurality of other wires, but with different frequency of coiling to a given length for the 65 attainment of the objects set out in the initial portion of this specification, and by noting the particular points of the intersections of the wire 5 with the four other wires at the 70 top or front of the roll denoted by the numbers 10, 11, 12, and 13 it will be seen that the intersections or apexes of the spaces within the crossing wires have a spiral trend for inducing a longitudinal rather than a radial forcing of the moisture accumulating during 75 use in the dandy-roll.

Having thus described my invention, what I claim, and desire to secure by Letters Patent, is—

1. A supporting structure for a dandy-roll 85 consisting of a series of separated wires running spirally in the same direction from end to end of the roll, and another wire running spirally also in the same direction but with a different pitch or degree of spirality, and 90 intersecting, in contact with, and secured to, each of the first-named series of wires, substantially as and for the purposes set forth.

2. A supporting structure for a dandy-roll 95 consisting of a series of wires 1, 2, &c., running in separated parallel spiral coils in the same direction, and another wire 5 having coils running in the same direction as the first-named wires, but of different frequency or degree of spirality, and intersecting and 100 in contact with the coiled wires of the first series, said wire 5 alternately crossing over and under the other wires, and every wire which is innermost at its place of intersection being formed with the bend or crimp 105 whereby the major portion of the length of all of the wires are conformable to the surface of a cylinder, substantially as described.

Signed by me at Springfield, Massachusetts, this 20th day of December, 1901.

FRANK H. BILLS.
